UNITED STATES PATENT OFFICE.

JOHN ELLWOOD LEE, OF CONSHOHOCKEN, PENNSYLVANIA, ASSIGNOR TO
THE J. ELLWOOD LEE COMPANY, OF SAME PLACE.

SPECULUM.

SPECIFICATION forming part of Letters Patent No. 449,941, dated April 7, 1891.

Application filed January 31, 1891. Serial No. 379,808. (No model.)

To all whom it may concern:

Be it known that I, JOHN ELLWOOD LEE, a citizen of the United States, and a resident of Conshohocken, Montgomery county, Pennsylvania, have invented an Improved Surgical Speculum, of which the following is a specification.

My invention consists of certain improvements in the construction of that form of speculum usually known as the "Graves" speculum, in which one jaw of the speculum carries an adjustable forked piece, to which the other jaw is pivoted.

The main object of my invention is to so construct a speculum of this character as to lessen the number of separate parts with the view not only of simplifying and economizing the manufacture, but also of facilitating the surgical cleansing of the instrument after each operation.

In the accompanying drawings, Figure 1 is a side view, partly in section, of a Graves speculum constructed in accordance with my invention. Fig. 2 is an end view. Fig. 3 is a perspective view of the upper jaw and the detachable fork, showing the manner of uniting the two. Fig. 4 is a view of the fork detached, and Fig. 5 is a view of the adjusting-screw detached.

The lower jaw J of the speculum has the usual extension j at right angles to it to receive the stem f of the adjustable forked piece F, to be secured after adjustment by means of the usual thumb-screw S. The upper jaw K is usually pivoted to the extremities of the forked piece F by means of threaded or other detachable pivot-pins passing through openings in the ends of the forked piece and of the jaw. To avoid the use of these detachable pivot-pins, however, I form in one with or permanently and fixedly secure to the upper ends of the fork at the inner sides pins p. I form in the upper jaw of the speculum suitable openings o for the reception of these pins, and I make the forked arms and the rear end of the upper jaw of the speculum with just sufficient spring or elasticity to enable the pivot-pins to be sprung into or out

of the openings in the jaw. To facilitate this operation I form on the outer face of the upper jaw adjacent to and leading into one of the pivot-openings, as shown in Fig. 3, a guiding-groove o' with an inclined bottom, so that by first placing one of the pins of the forked piece into the other opening o in the jaw the pin p on the arm of the fork adjacent to the groove o' may be readily drawn into this groove o' and then sprung into the opening o, in which the groove terminates, as shown in Fig. 3. The upper jaw is, as usual, provided with the finger-piece or adjusting-arm k, while a screw L, carried by the corresponding arm of the fork, passes through a slot k' in this finger-piece. An adjusting-nut l' on the screw is adapted to bear on the finger-piece, as heretofore.

In order to facilitate the thorough surgical cleansing of the instrument and to enable the several above-described parts to be readily put together, I construct this adjusting-screw L with a conical or other shouldered head l', adapted to a corresponding opening in the arm of the fork through which it passes, as shown in Fig. 2, so that the adjusting-screw can be detached from the fork F and finger-piece k, and also from its adjusting-nut l.

I am aware that specula have heretofore been constructed with pivot-pins on one jaw adapted to be sprung into corresponding openings on the other jaw, the well-known Baxter speculum being an illustration of such a construction. This, therefore, I do not claim; but

I claim as my invention—

1. The combination of the upper jaw of a speculum with the lower jaw and the detachable forked piece, the latter having at its upper end pins permanently fixed thereto or forming part thereof and adapted to be sprung into corresponding openings in the upper jaw for the pivoting of the latter, all substantially as described.

2. The combination of the upper jaw of a speculum having pivot-openings and adjacent to one of such openings an inclined

groove with lower jaw, and the adjustable forked piece having pivot-pins permanently affixed to or formed in one with the arms of the forked piece and adapted to be sprung 5 into the openings in the upper jaw through the aid of the inclined groove, substantially in the manner hereinbefore described.

In testimony whereof I have signed my name to this specification in the presence of two subscribing witnesses.

JOHN ELLWOOD LEE.
